UNITED STATES PATENT OFFICE

ALCEO BRISIGHELLI, OF CORDOBA, ARGENTINA.

LIFE-PRESERVER.

SPECIFICATION forming part of Letters Patent No. 659,127, dated October 2, 1900.

Application filed February 9, 1900. Serial No. 4,638. (No model.)

To all whom it may concern:

Be it known that I, ALCEO BRISIGHELLI, a subject of the King of Italy, and a resident of Cordoba, Argentina, have invented new and 5 useful Improvements in Life-Preservers, of which the following is a full, clear, and exact description.

My invention relates to life-preservers, and has for its object to provide a simple device 10 adapted to act automatically when submerged in water to generate gas which will inflate the life-preserved.

The invention will be fully described hereinafter and the features of novelty pointed 15 out in the appended claims.

Reference is to be had to the accompanying drawings, forming a part of this specification, in which similar characters of reference indicate corresponding parts in all the figures.

20 Figure 1 is a perspective view of my improved life-preserved. Fig. 2 is a central vertical section through the gas-generator. Fig. 3 is a front elevation of the gas-generator, and Figs. 4 and 5 are detail views of certain 25 parts of the generator.

The life-preserved comprises a suitable inflatable tube or casing A, made of rubber or of any other fabric of sufficient imperviousness, and of a gas-generator B, secured to said 30 casing. The casing is generally made of a proper size to fit around a person's body under the arms like an ordinary life-preserved.

The generator comprises a water-receptacle C, having in its front or outer wall an aperture, through which extends a tube or socket D, secured to said front wall. At its front end said socket has a screw-thread D', into which fits a screw-cap E, provided with a milled head E'. This cap has through-apertures E², 35 leading from its front face to its rear face, as shown in Fig. 4, which is a rear view of the cap. In the socket D is further movable longitudinally a piston F, connected with a rod F', which at its rear end carries a valve G, 40 adapted to close the open rear end of the receptacle C. This valve, as shown, consists of three layers held together by nuts H. At the rear end of the socket D the rod F' passes through a stuffing-box I, having a gasket I'. 45 A spring F² is coiled on the rod F' between the piston F and the rear end of the socket D. Furthermore, the rod F' carries a cross-

bar J, secured to it rigidly and engaging the walls of the receptacle C to form a guide for the rod F'. 55

The receptacle C has an annular flange C' projecting from it, and in the rear of said flange is a screw-thread C² for the purpose of making connection with the inner or carbide receptacle K. This receptacle is entirely 60 open at the front, so that it is readily accessible after the water-receptacle C has been screwed off. Adjacent to the flange C' the receptacle K has an annular flange K', forming a shoulder, against which is seated the 65 edge of the inflatable tube A. At some portion which is within the tube A, preferably at its upper wall, the receptacle K is provided with apertures K².

To fill the apparatus, so that it will be ready 70 for use, the water-receptacle C is screwed off and a suitable amount of a substance adapted to give off gas when in contact with water, such as calcium carbide, is filled into the receptacle K, as indicated at M. The receptacle C is filled with water through the opening in its rear end, the spring F² holding the valve G open at that time, the cap E being removed. Then, preferably while the open 75 end of the receptacle C is lowermost, a suitable compound soluble in water or capable of decomposing it—such as potassium, sodium, or calcium carbide—is introduced into the socket D on the outside of the piston F, as indicated at N. The cap E is then screwed 80 in by means of the head E', thus compressing the filling N and the spring F² and causing the valve G to become firmly seated, so that the water cannot reach the carbide even when the receptacle is shaken or inclined. The receptacle C is then again screwed into the receptacle K. The apparatus is then ready for 85 use. A person has nothing to do but to slip the life-preserved around the body. As soon as the person is in the water the outer end of 90 the socket D will be submerged and water will pass through the apertures E² of the cap E to the filling N. This filling will by 95 dissolving or decomposition remove the resistance opposed to the outward movement of the piston F, and the valve G will be moved outward by the spring F². This will allow 100 water from the receptacle C to pass into the carbide-receptacle K to generate acetylene.

gas, which through the apertures K² will enter the casing A and inflate the same. The wearer will thus be kept from sinking. The inflation, as I have found by experiment, 5 takes place in a very short time—about eight or nine seconds.

The carbid should be in the shape of small lumps or fragments to secure a ready generation of gas.

10 Various modifications may be made without departing from the nature of my invention as set forth in the appended claims.

Having thus described my invention, I claim as new and desire to secure by Letters

15 Patent—

1. A life-preserved, consisting of an inflatable casing, and a gas-generator comprising a generating-receptacle carried by the said casing and communicating with the interior 20 thereof, a liquid-receptacle, having a valve-controlled connection with the generating-receptacle, a filling which when dry keeps the valve closed and when wetted allows it to open, and a perforated cap for holding said filling 25 in position.

2. A life-preserved, consisting of an inflatable casing, and a gas-generator comprising a generating-receptacle carried by the said casing and communicating with the interior 30 thereof, a liquid-receptacle communicating with the generating-receptacle, a valve for closing said communication, a spring for opening the valve, a filling which when dry opposes the action of the spring and keeps the 35 valve closed, and when wetted allows it to open, and a perforated cap for holding said filling in position.

3. A life-preserved, consisting of an inflatable casing, and a gas-generator comprising a generating-receptacle carried by the said 40 casing and communicating with the interior thereof, a liquid-receptacle communicating with the generating-receptacle, a valve for closing said communication, a rod connected with the valve, a socket secured to the liquid-receptacle and into which extends the valve-rod, a piston secured to the rod within the socket, a spring coiled on the rod within the socket between the piston and the valve, and a perforated cap screwing into the outer end 45 of the socket.

4. A life-preserved, consisting of an inflatable casing, and a gas-generator comprising a generating-receptacle carried by the said 55 casing and communicating with the interior thereof, a liquid-receptacle communicating with the generating-receptacle, a valve for closing said communication, a rod connected with the valve, a socket secured to the liquid-receptacle and into which extends the valve-rod, a piston secured to the rod within the socket, a spring coiled on the rod within the socket between the piston and the valve, a guide-bar secured to the rod between the valve and the socket and engaging the liquid-receptacle, and a perforated cap screwing into 60 the outer end of the socket.

In testimony whereof I have signed my name to this specification in the presence of two subscribing witnesses.

ALCEO BRISIGHELLI.
